CAP FOR FLEXIBLE TUBES

Filed Sept. 27, 1924

O. H. Hosmer ^{Inventor}
By *Chasnow & Co.*
Attorneys

UNITED STATES PATENT OFFICE.

ORVILLE H. HOSMER, OF ST. PAUL, MINNESOTA.

CAP FOR FLEXIBLE TUBES.

Application filed September 27, 1924. Serial No. 740,311.

By way of explanation, it may be stated that in the opening of tubes of the kind in which tooth paste and other materials are contained, it is necessary for the operator to hold the tube in one hand and detach the cap with the other hand, work thus being provided for both hands of the operator.

The foregoing being understood, this invention aims, generally stated, to provide a

10 tube and a closure which are so constructed that the thumb or one of the fingers of the hand which is holding the tube, may be used to open the closure, the other hand of the operator remaining free.

15 It is within the province of the disclosure to improve generally and to enhance the utility of devices of that type to which the invention appertains.

With the above and other objects in view, 20 the invention consists in the novel construction and arrangement of parts hereinafter described and delineated in the drawings, it being understood that it is impossible to show all forms which the invention may 25 take, and it being understood that, within the scope of what is claimed, a mechanic may make changes in the form selected as an illustration, without departing from the spirit of the invention.

30 In the accompanying drawings:—

Figure 1 shows in side elevation, a device constructed in accordance with the invention, parts being broken away, and the closure being in section; Figure 2 is an elevation wherein the device is viewed at right angles to the showing of Figure 1, parts being broken away; Figure 3 is a top plan; and Figure 4 is a section through the hinge lug on the tube.

40 In the accompanying drawings, the numeral 1 designates a flexible tube of the kind in which tooth paste or other merchandise is contained. The tube 1 has a neck 2 having a circumferential shoulder 3. The top 4 of the tube or container 1 is supplied, near to its edge, with an upstanding lug 5 having seats 6 in its sides.

The device comprises a cup-shaped closure 7 adapted to fit closely on the neck 2. Slits 8 extend upwardly from the lower end of the closure 7 and define resilient tongues 9,

adapted to grip the neck 2 of the tube 1 and to engage with the shoulder 3, to hold the closure securely but releasably on the neck 2. A compressible gasket 10 is secured in the 55 closure 7 and is adapted to engage the end of the neck 2 of the tube 1, to prevent leakage. The closure 7 is provided adjacent to its outer end with a circumferential groove 11.

The closure 7 is mounted on the tube 1 through the instrumentality of a hingedly constructed carrier which is denoted generally by the numeral 12. The carrier 12 may be constructed as desired, but in the present 60 form of the invention, it is made out of a piece of spring wire, bent upon itself to form a loop-shaped handle 14, the side portions of the handle being crossed upon each other as at 15, to fashion arcuate jaws 16 65 received in the groove 11 of the closure 7. One of the jaws 16 is prolonged to form an arm 17, and the other of the jaws is prolonged to form an arm 18, the arm 18 having an open loop 19 engaged about the arm 17. 70 The arms 17 and 18 terminate in inwardly extended pivot fingers 20, received in the seats 6 of the lug 5, the carrier 12 thus being mounted hingedly on the tube 1.

In practical operation, the arms 17 and 18 80 of the carrier 12 are bowed as at 21, and are put under spring tension, the closure 7 being seated on the neck 2 and the spring tongues 9 engaging the shoulder 3, as shown in Figure 2. The operator holds the tube 1 in his hand, and swings the carrier 12 upwardly, by thumb pressure exerted beneath the handle 14, the tongues 9 of the closure 7 being disengaged from the shoulder 3, and the carrier 12 tending to straighten, and to fly 85 to an open position, because the arms 17 and 18 of the carrier are resiliently bowed as at 21. Owing to the fact that the arm 18 is provided with the open loop 19 engaged about the arm 17, the jaws 16 may be separated for mounting in the groove 11 of the closure 7.

Having thus described the invention, what is claimed is:—

In a device of the class described, a receptacle having a neck, a closure detachably engaged with the neck, and a carrier hinged to

the receptacle, the carrier being fashioned from a single piece of material formed into a loop-shaped handle, the sides of the handle being crossed on each other and being prolonged to form arcuate jaws engaging the closure, the jaws being extended to form arms, one of which has an open loop receiv-

ing the other, the arms terminating in means for engaging the receptacle hingedly. In testimony that I claim the foregoing ¹⁰ as my own, I have hereunto affixed my signature.

ORVILLE H. HOSMER.
